UNITED STATES PATENT OFFICE.

ANDREW C. ROSS, OF ALMONT, MICHIGAN.

SAWING-MACHINE FOR RESAWING BOARDS.

Specification of Letters Patent No. 24,240, dated May 31, 1859.

To all whom it may concern:

Be it known that I, ANDREW C. ROSS, of Almont, in the county of Lapeer and State of Michigan, have invented a new and useful Machine for Resawing Boards, Planks, or other Articles; and I do hereby declare that my said invention is fully described and represented in the following specification and accompanying drawings, letters, figures, 10 and references thereof.

Figure 1 of the accompanying drawings exhibits a top view of my invented resawing machine. Fig. 2 is a longitudinal section of it. Fig. 3 is a perspective view of it.

15 In the said drawings of Figs. 1, 2 and 3 A represents the main frame of the machine of which B B is a stationary platform or bed fixed on the top part of the main frame. At a suitable distance is placed the upper 20 rotary plane cylinder or cutter C and made to operate the said plane has its journals and is supported in boxes a a. There is an opening transversely made through the platform B B in which a rotary cutter or plane 25 D is placed below and within the said openings and made to revolve in such manner as to carry its cutters against the underside of the board plank or other article and reduce it or remove the wood therefrom. For impelling the board toward and past the rotary planes or cutters the saws jointers or matchers and stickers I employ one or more sets 30 of feed rollers E F. The roller E is made so as to freely revolve on its journals while 35 in other respects it is stationary, the other roller F is not only capable of rotating but of rising and falling so as to adapt itself to the varying thickness of the board plank or other article for this purpose it is borne 40 down toward the other roller by means of one or more weighted levers and suitable bearing rods such as are in common use for such purpose.

The main driving shaft is placed at G as 45 seen in drawings at one end it has a large pulley, on the center of said shaft there is fixed a large drum around which two endless belts pass, and thence pass around two pulleys c c fixed on the shaft of the upper 50 rotary plane C around said drum two endless crossed belts pass and thence pass around two pulleys d d fixed on the shaft of the under planing cylinder around said drum pass two endless belts and thence 55 pass around two pulleys e e fixed on the vertical shafts whereon the saws are made to operate, the said vertical shafts having fixed on them two other pulleys f f around each of which one of two endless belts pass and thence pass around one of two pulleys 60 g g fixed on the vertical shafts of the jointers or matchers H H. On the shaft of the upper rotary plane C is fixed a pulley h around which an endless belt is passed and thence passes around a pulley i on the shaft of the 65 upper sticking cylinder I. On the shaft of the lower rotary plane D is fixed a pulley j around which an endless belt passes and thence passes around a pulley k fixed on the shaft of the lower sticking cylinder K by the 70 aforesaid means of pulleys and belts the said upper and lower cylinders the saws the jointers or matchers, and the upper and lower sticking cylinders the whole being as seen in the drawings and is put in rapid revolution 75 when the main shaft is made to revolve.

On one end of the axle of the lower feed roller a large gear wheel l is fixed the same being made to engage with a toothed pinion m. Fixed on a transverse horizontal 80 shaft which plays or rotates in boxes and has a pulley n on its end, an endless crossed belt passes around the pulley l and also around a pulley fixed on the end of the driving shaft the whole being as seen in the drawings by such means the lower feed 85 roller is revolved when the main shaft is put in rotation. By means of feed rollers E and F the plank is advanced or moved upon the bench B B and under the rotary 90 plane C the said plank by means of pressure rollers being firmly held down by spring bars, said rollers yielding to the variation of thickness of the plank as it passes under them. Over or in the vicinity of the lower 95 rotary plane is arranged transversely a roller O said roller being kept down by spring bars upon the plank while the said plank rests on the bed B B the under surface or part of the board is reduced to parallelism with the upper surface of it which always throughout the operation rests on the bed or platform B B which prevents the board being drawn downward and toward the rotary cutter. At a suitable distance 100 from the said rotary cylinder is placed and made to operate the circular saws K, the said circular saws have their shafts p supported in boxes confined in vertical swinging or adjustable frames R and two horizontal and transverse bars or bridgetrees s the frames being respectively supported in 105 110

stationary guides or slots in said bars or bridgetrees and fastened on the main frame and so made as to allow of a free horizontal movement either inward or outward of the 5 said frames. The distance between the platform and the underside of the saws determines the thickness of a board while in the operation of resawing and for the purpose of resawing a board or plank to any 10 desirable thickness as circumstances may require either beveled or parallel the saws may be provided with suitable mechanical contrivances by which their distance from the platform or bed may be adjusted or 15 regulated. The mode of accomplishing this I have exhibited in the enlarged drawings. It consists in screws t being tapped into and through the top parts of the flanges z, z of the saws and made to screw against the 20 top of the shafts supporting said saws. The said saws being respectively secured to said shafts by means of a feather or small screw fastened on one side of the flange and so made as to allow of a free vertical move- 25 ment either upward or downward in a slot or seat made for that purpose in said vertical shaft. On the opposite side of said flange I use one or more set of punch screws tapped into and through said flange and 30 made to screw against said shaft by such means the said saws are properly arranged and secured when put in rotation. A horizontal bar or separator L is arranged with its lower surface a little lower than the 35 lower surface of the circle of revolution of the cutting edge of the circular saws. The said bar is arranged in the rear of said saws and across the machine and is fastened firmly at its ends by screws to spring bars.

The board as it advances beyond the saws 40 one part passes between the bed and rest bar and the other part above the said rest bar and the said board or plank, is kept firmly down to the bed and up to the guide by means of said bar while in the operation of resawing thereby giving it a perfect thickness 45 throughout its length.

At a suitable distance from the saws is placed the jointers or matchers I, I these are placed there for the purpose of jointing 50 boards or plank and bringing them to a perfect breadth throughout their length. And further for the purpose of tonguing and grooving flooring ceiling &c. The upper and lower sticking cylinders H are placed at a suitable distance from the jointers and may be used one or both of them as circumstances may require, for the purpose of beading sticking moldings or finishing 55 strips for gothic houses.

In arranging the saws for resawing I employ two or more saws by this means I am enabled to use a much thinner saw and save material and power to a great extent.

I do not claim the employment in one machine of rotary planers, tonguing, grooving and rabbeting devices, and sticking or beading devices, but

What I do claim as my invention and desire to secure by Letters Patent, is—

The arrangement of circular saw K , stationary divider L , in connection with a permanent horizontal bed, in resawing machines, for the purposes set forth.

ANDREW C. ROSS.
